UNITED STATES PATENT OFFICE.

MICHAEL A. NORKUNAS, OF BROCKTON, MASSACHUSETTS.

DESIGN FOR A SOCIETY-EMBLEM.

46,960.

Specification for Design.

Patented Feb. 16, 1915.

Application filed October 29, 1914. Serial No. 869,326. Term of patent 7 years.

To all whom it may concern:

Be it known that I, MICHAEL A. NORKUNAS, a citizen of the United States, residing at Brockton, in the county of Plymouth and State of Massachusetts, have invented a new, original, and ornamental Design for a Society-Emblem, of which the following is a specification, reference being had to the accompanying drawing, forming part thereof.

The figure is a front view illustrating my new design.

Copies of this patent may be obtained for five cents each, by addressing the "Commissioner of Patents, Washington, D. C."

I claim:

The ornamental design for a society emblem, as shown.

In testimony whereof I have hereunto set my hand in presence of two subscribing witnesses.

MICHAEL A. NORKUNAS.
